UNITED STATES PATENT OFFICE

2,604,691

APPLIANCE FOR AUTOMATIC LATHES

André Bechler, Moutier, Switzerland

Application September 23, 1946, Serial No. 698,814
In Switzerland July 23, 1946

4 Claims. (Cl. 29—41)

1

In automatic lathes drilling appliances with several working spindles such as tool-holders capable of being brought successively into alignment with the headstock spindle axis are used either to bore holes of different size, or to tap or enlarge a hole after it has been made. In all types of appliances of this kind known up to the present day, the position of the working spindle, or spindle of the drill-holder, relative to the piece of work, was controlled by a lever-arm with follower riding on the contour of a cam lobe. It sometimes happens that the surface of the cam is not absolutely clean, or is a little rough, causing an increase in the diameter of its lobe, so that alignment of the tool and the work is inaccurate.

The object of the present invention is to provide means which make the position of the axis of each working spindle independent of the state of the working surface of the cam. To this end, a tool-box containing the working spindles is adapted to be abutted by controlling levers, abutment being effected by a spring, each of these levers having a cam follower resiliently connected therewith, and each cam follower being actuated by a cam. The working range of each lever is regulated by means of an adjustable stop-screw.

The drawing shows, by way of example, an embodiment of a drilling appliance with several working spindles according to the invention.

Fig. 1 is a side-elevation of the appliance, partly in section along the broken line I—I in Fig. 2.

Fig. 2 is an end-elevation of the same, as seen from the back end of the lathe, partly in section along the line II—II in Fig. 1.

Fig. 3 is a plan view of the same, partly in section along the line III—III in Fig. 1.

Fig. 4 is a partial end-view of the appliance as shown in Fig. 1.

With reference to the drawing, the frame 10 of the lathe, of which a portion only is represented, carries a bracket 11 on which the drilling appliance is mounted. The latter comprises a tool box 12, in the two cheeks of which working spindles such as tool holders 13, 14 and counter gears 15, 16 are rotatably mounted. Gear wheel 16 is keyed on axle 17 carrying a rope pulley 18 for driving the tool holders. The tool box 12 rocks on pivots 17 and 19, the latter being in the form of a gudgeon coaxial with the former and carried in a support 20 formed by the lower part of the tool box 12. A lateral arm 22 (see Fig. 2) projecting from the support 20 carries a pin 23 which is abutted by the bent ends 24 of the levers 25 pivoted on shaft 26 carried in supports 27 and 55

2

28 cast integral with the bracket 11. Arm 22 extends opposite to the cam-shaft side of the mechanism, so that the swing axis 26 of levers 25 is disposed between the cam shaft 33 and the swing axis 17 of the tool box.

The levers 25 are provided with followers 29 carried at the extremities of springs 30 which are secured to the levers by screws. Each follower rides on the one of the cams 31 and 32 10 fixed on camshaft 33 which carries a cylindrical cam 34 cooperating with a lever 35, pivoted at 36. Lever 35 carries a pin 37 for actuating the tool holders 13 and 14 when they are in alignment with the pin (see Fig. 4).

15 The tool box 12 is not rigidly connected with the levers 25. It is forced against the angle-shaped ends 24 of the latter by a spring 38 attached, at one end, to a bolt 39 extending from bracket 11, and at the other end, to an ear 20 provided on the tool box. Stop-screws 41, 42 are inserted in the base plate of the bracket 11 individually, limiting the motion of levers 25.

The appliance shown in the drawing functions as follows: The rope pulley 18 revolves 25 the tool holders 13 and 14 continuously. The cylindrical cam 34 acting through the lever 35 causes the pin 37 to axially displace one or the other of the tool holders 13 or 14, i. e. the one which happens to be in alignment with it. In the drawing, 13 is shown about to be pushed 30 into working position. For placing the tool holder 14 in working position, cam 32 lifts the lever 25 whose follower rides on cam 32 and lowers the end 24 of the lever for depressing pin 23 projecting from the tool box 12 and swinging 35 the latter clockwise as seen in Fig. 2, independently of the position of the other lever whose follower rides on cam 31. The effect of cam 32 is limited by stop screw 42 which accurately determines the operating position of 40 spindle 14. The disposition of the moving parts represented in the drawing effects exact operating position of the tool holder 13 which is independent of any roughness of the cam 31, because of the cam presses the lever by means 45 of leave spring 38 against the stop-screw 41 and continues to bend the spring 38 without any effect on the box, spring 38 forcing pin 23 rigidly connected with the box against the end 24 of the lever. Likewise, the combination of the invention assures independence of the operating 50 position of spindle 14 from the cam after the spindle is in its operating position if cam 32 actuates its lever 25, whose motion is limited by the stop-screw 42.

The number of working spindles represented

in the drawing is two; there is no reason why this number should not be increased to some reasonable extent.

What I claim is:

1. An automatic lathe comprising, in combination, a support, a tool holder swingably mounted on said support, a shaft mounted on said support and having a rotation axis parallel to the swing axis of said tool holder, a plurality of cams mounted on said shaft, a plurality of levers, one for each of said cams, said levers being individually swingable about an axis parallel to the rotation axis of said shaft and adapted to individually abuttingly engage said tool holder eccentrically of its swing axis, each lever having a cam follower resiliently connected to it and engaging one of said cams, adjustable stop means, one for each lever, connected with said support for limiting the extent of movement of each lever, and means tending to swing said tool holder in a direction for abutting at least one of said levers.

2. An automatic lathe as defined in claim 1, in which the swing axis of said levers is disposed between said shaft and the swing axis of the tool holder.

3. An automatic lathe as defined in claim 1, comprising leave springs, one for each lever, for resiliently connecting said cam followers and said levers.

4. An automatic lathe as defined in claim 1, comprising a drive shaft extending through said tool holder coaxially of its swing axis, a plurality of tool spindles disposed equi-distantly and parallel to said drive shaft and being rotably and axially displaceably supported by said tool holder, and gear means interposed between said drive shaft and said tool spindles and affording drive of the latter by the former at all relative axial positions of the tool spindles and tool holder.

ANDRÉ BECHLER.
